US00D995060S

(12) **United States Design Patent** (10) **Patent No.:** **US D995,060 S**
(45) **Date of Patent:** **** Aug. 15, 2023**

(54) **SHOE**

(71) Applicant: **ROTHY'S, INC.**, San Francisco, CA (US)

(72) Inventors: **William Roth Martin**, San Francisco, CA (US); **La Vion Gibson**, San Francisco, CA (US); **Erin D. Lowenberg**, San Francisco, CA (US)

(73) Assignee: **ROTHYS, INC.**, San Francisco, CA (US)

(**) Term: **15 Years**

(21) Appl. No.: **29/831,309**

(22) Filed: **Mar. 18, 2022**

Related U.S. Application Data

(63) Continuation of application No. 29/748,906, filed on Sep. 1, 2020, now Pat. No. Des. 949,526.

(57) **CLAIM**

The ornamental design for a shoe, as shown and described.

DESCRIPTION

FIG. 1 is a front right perspective view of an embodiment of a shoe showing our new design;

FIG. 2 is top view of the design shown in FIG. 1;

FIG. 3 is a bottom view of the design shown in FIG. 1;

FIG. 4 is a right side view of the design shown in FIG. 1;

FIG. 5 is a left side view of the design shown in FIG. 1;

FIG. 6 is a front view of the design shown in FIG. 1; and,

FIG. 7 is a rear view of the design shown in FIG. 1.

The broken lines shown in the Figures are included for the purpose of illustrating portions of the shoe that form no part of the claimed design. Colors forms no part of the claimed design.

1 Claim, 7 Drawing Sheets
